UNITED STATES PATENT OFFICE

ERNST AUGUST LEHMANN, OF FRIEDRICHSHAFEN, BODENSEE, GERMANY, ASSIGNOR TO
LUFTSCHIFFBAU ZEPPELIN GESELLSCHAFT MIT BESCHRANKTER HAFTUNG, OF
FRIEDRICHSHAFEN, BODENSEE, GERMANY

AIRSHIP

Application filed July 18, 1931, Serial No. 551,650, and in Germany July 21, 1930.

My invention relates to airships and has special reference to gas-inflated aircraft the inner space of which is longitudinally subdivided into individual compartments.

5 The main object of my invention is an advantageous distribution of the different gas cells with the gas they contain over the length of the ship, especially with ships in which two kinds of buoyant gases are used in combination with a fuel gas for feeding the motors.

10 Of course, it is best to use only a non-inflammable gas, such as helium, as lifting gas. But it is expensive and comparatively heavy, so that in many cases it is advisable to make 15 use of the cheaper and lighter hydrogen also. Consequently, in such cases three kinds of gas have to be distributed over the inner space of the ship's hull and gas cells of adequate material have to be provided therefor.

20 According to my invention the different gas containers and the gases with which they are inflated are so distributed longitudinally of the airship that there are always at least two neighbouring cells inflated with fuel gas. 25 This fuel gas is always heavier than the lifting gases. It is therefore preferred to have the fuel gas containers in the lower portions of the compartments.

Between two pairs of fuel gas cells there 30 should be at least one hydrogen container, whereas the helium containers preferably are provided in the upper portions of the compartments.

The drawings represent examples embodying my invention. They are drawn in a more diagrammatical manner. Figs. 1 and 2 are longitudinal vertical sections through the hull of a rigid airship. Fig. 3 shows the middle portion of Fig. 2 but on an enlarged 40 scale.

The first example is represented in Fig. 1, whereas Figs. 2 and 3 give another example.

The outer contour of the ship is indicated at 1 (the hull construction is not shown). 45 All the upper gas cells 2 are inflated with helium, whereas the lower cells 3 contain hydrogen. The fuel gas is stored in the lower gas cells 4, wherefrom it is fed to the motors in the cars 5 by means of pipelines or 50 ducts 6.

The material for the cells containing the heavier fuel gas can be lighter than that containing the lighter helium, whereas the material for enveloping this gas can again be lighter than the envelopes for the hydrogen 55 gas.

Gas ducts 7 serve for guiding the hydrogen gas escaping through the valves 8 to the top of the ship.

Between a helium gas cell above a fuel gas 60 cell and a neighbouring helium gas cell above a hydrogen gas cell a communication, for example a valve 9 is provided. This arrangement has the advantage that, after hydrogen has escaped, the helium gas may expand 65 downwardly into the space formerly filled with hydrogen. This means a considerable saving in the costly helium gas in the operation of such a ship.

In the example shown in Fig. 1 the pairs of 70 fuel gas cells are separated by one hydrogen gas cell, whereas in the example represented in Figs. 2 and 3 always two hydrogen gas cells are inserted between two pairs of fuel gas cells. At the forward and rear end of 75 the ship the lower gas cells preferably are provided to be inflated with hydrogen and not with fuel gas, because here buoyancy is wanted.

The hydrogen gas cells according to my invention are situated at a very advantageous place in the hull where it is easy and convenient to supervise them. Besides only hydrogen is intended to escape from the ship and none of the expensive helium. Furthermore 85 the fuel gas is situated not far from the engines where it is consumed.

Thus the distribution according to my invention is most advantageous.

Of course, I do not want to be limited to 90 the exact details described or shown in the drawings as variations will occur to those skilled in the art.

What I claim is:

1. In an airship subdivided longitudinally 95 into individual compartments, gas cells inflated with non-inflammable lifting gas in the upper portions of said compartments, and gas cells inflated with an inflammable lifting gas and gas cells inflated with a heavier fuel 100

gas for the motors in the lower portions of said compartments; said fuel gas cells being arranged in pairs between which at least one gas cell containing inflammable lifting gas is inserted.

5. 2. Gas cell arrangement as claimed in claim 1 further characterized by the feature that the gas cells containing inflammable lifting gas are also arranged in pairs.
